UNITED STATES PATENT OFFICE

JULIUS CUCHRAN AND HENRY HINTERKOPF, OF CHICAGO, ILLINOIS

DESIGN FOR A GAME BOARD

Application filed August 4, 1932. Serial No. 44,520. Term of patent 3½ years.

To all whom it may concern:

Be it known that we, JULIUS CUCHRAN and HENRY HINTERKOPF, citizens of the United States, residing at Chicago, in the county of Cook and State of Illinois, have invented a new, original, and ornamental Design for a Game Board, of which the following is a specification, reference being had to the accompanying drawing, forming part thereof.

Fig. 1 is a plan view of the game board showing our new design; and

Fig. 2 is an edge view of the same.

We claim:

The ornamental design for a game board as shown.

JULIUS CUCHRAN.
HENRY HINTERKOPF.
